UNITED STATES PATENT OFFICE.

AUGUST M. AUGENSEN, OF MAYWOOD, ILLINOIS, ASSIGNOR TO SANITARY CAN COMPANY, OF NEW YORK, N. Y., A CORPORATION OF NEW YORK.

CAN-BODY-FEEDING MECHANISM.

1,134,028.

Specification of Letters Patent. Patented Mar. 30, 1915.

Application filed June 20, 1912. Serial No. 704,905.

To all whom it may concern:

Be it known that I, AUGUST M. AUGENSEN, a citizen of the United States, residing in Maywood, in the county of Cook and State 5 of Illinois, have invented a new and useful Improvement in Can-Body-Feeding Macha- nism, of which the following is a specifica- tion.

This invention relates to improvements in 10 can body feeding mechanisms and relates more particularly to that type of feeding mechanism used in connection with corn or other filling machines.

The object of the invention is to provide 15 a mechanism which will feed cans at a very high speed in an upright position, one at a time, with the open ends up, to a table or platform connected with the filling machine, and to accomplish this feeding without in- 20 jury to the can bodies.

The improvements furthermore consist in the parts and devices and in the novel combinations of parts and devices herein shown, described or claimed.

25 In the drawing forming a part of this specification, Figure 1 is a plan view of a mechanism embodying my improvements. Fig. 2 is a side elevation of the structure shown in Fig. 1. Fig. 3 is a sectional view, 30 taken on the line 3—3 of Fig. 2, and looking in the direction of the arrows, and Fig. 4 is a section on the line 4—4 of Fig. 2.

In the drawing, A represents the guide- 35 way adapted to support can bodies or other articles in a vertical position, the same being composed of a plurality of angle bars 10, 10 and strap irons 11, 11, the supporting guide way forming preferably the lower end of a gravity feed chute down which the 40 can bodies or other articles are adapted to feed, and said guide way is provided at its inner end with a circular recess or orifice 12 through which the can bodies or other articles are adapted to drop onto a continuously 45 rotatable table or platform 13 connected to the filling machine and provided with a plu- 50 rality of vane or arms 14, whereby the can bodies may be propelled to a position to be filled. The can bodies or other articles feed down the chute A by gravity and are tem- 55 porarily restrained from continuing their movement by suitable means, such, for instance, as a vertically reciprocating member 15 having a pair of fingers 16, 16 which ex- 60 tend into the guide way and engage the

front side of the can body or other articles, 65 said member 15 having a depending arm 17 slidably mounted in the bracket 18, and adapted to be moved up and down by means of a pivoted lever 19, the latter being nor- 70 mally held in an upward position by a spring 20 secured to the lever and to a sta- 75 tionary part of the bracket 18. Also mount- 80 ed in the bracket 18 are a pair of vertically extending shafts 21, 21 located on opposite 85 sides of the guide way and each provided with an arm 22 at its upper end, said arms having a path of movement extending over the guide way A and adapted to engage the 90 can bodies or other articles, and so disposed 95 that the arms alternately extend over the guide way. Each of the shafts 21 has se- 100 cured thereto at its lower end a gear 23, the same being suitably geared together by pin- 105 ions 24, and adapted to be driven from a gear 25 secured to the lower end of one of the 110 shafts of one of the pinions 24, said gear 25 being in turn driven from a gear 26, and the latter in turn driven from a gear 27 preferably mounted on the shaft supporting 115 the table or disk 13 and driven by any suit- 120 able means from any moving part of the can filling machine to which the feeding mech- 125 anism is attached. One of the vertically ex- 130 tends shafts 21 is provided at its lower 135 end with a double cam 28 to operate the lever 19 by a pin 29 mounted in the free end of the 140 lever 19, whereby the projections or fingers 16 are reciprocated up and down twice dur- 145 ing each complete rotation of one of the 150 shafts 21.

In operation, the can bodies B feed down 155 the gravity chute and are temporarily held by the stops 16 until engaged by one of the 160 arms 22, whereupon the mechanism is so 165 timed that the stops 16 will be depressed and the can body given a sharp shove which 170 projects the can body to a position over the 175 recess 12, whereupon the can body drops 180 down onto the table 13 and is then trans- 185 ferred to a position beneath the filling nozzle 190 of the filling machine, it being understood 195 that all the parts are properly timed so that 200 the operations may be continued indefinitely 205 as the can bodies feed down the gravity 210 chute.

I have described one form of mechanism 215 adapted to attain the objects hereinbefore set forth, but, as will be obvious to those skilled in the art, many changes and varia- 220

tions may be made in the details thereof without departing from the spirit of the invention, and all such changes and variations are contemplated as fall within the 5 scope of the claims appended hereto.

I claim:

1. In a device of the class described, in combination, an article supporting guideway, a pair of rotating shafts mounted on 10 opposite sides of said guideway, each shaft being provided with a projecting arm movable in a path above the guideway and adapted to engage articles therein, mechanism connected with the said shafts where- 15 by the arms are caused to pass alternately across the same space to engage alternate successive articles of a row of such articles as they arrive at the said space, and means for temporarily preventing the passage of 20 an article along the guideway.
2. In a device of the class described, in combination, a horizontally extending article supporting guideway having a recess therein through which the articles are 25 adapted to drop by gravity, and a rotating shaft located adjacent the guideway and provided with a projecting arm movable in a path above the guideway and adapted to engage articles therein, and means for tem- 30 porarily preventing the passage of articles along the guideway.
3. In a device of the class described, in combination, a gravity feed chute having a horizontal portion at the bottom thereof and provided with a recess therein through 35 which the articles are adapted to drop by gravity, a rotating arm having a path of movement above said horizontal portion of the guideway and adapted to engage the 40 articles therein, and means located adjacent said rotating arm adapted to temporarily prevent the passage of articles along the guideway.
4. In a device of the class described, in combination, a horizontally disposed can 45 body supporting guideway provided with a recess therein through which the can bodies are adapted to drop by gravity, a plurality of rotating arms having a path of move- 50 ment above the guideway and adapted to alternately engage the can bodies therein, means for temporarily preventing the can bodies from moving along said guideway and a table located below the recess in the 55 guideway onto which the can bodies are adapted to fall after they pass through the recess.
5. In a device of the class described, in combination, a can body gravity feed chute 60 having a horizontally extending portion at the lower end thereof and provided with a recess through which the can bodies are adapted to fall by gravity, a pair of ver-

tically extending rotating shafts located on opposite sides of said horizontal portion 65 of the guideway, each of said shafts being provided with a projecting arm adapted to alternately engage the can bodies while in said guideway, and means for temporarily preventing the can bodies from moving 70 along the guideway, said means comprising a vertically reciprocating member adapted to be moved into and out of the guideway.

6. A timing and feeding mechanism of the character described including, in combination: a gravity feed chute having a horizontal portion at the bottom thereof; means for temporarily stopping articles on 75 said horizontal portion as the same come down the gravity feed chute; a rapidly rotatable member having a path of movement above said horizontal portion adapted to engage the articles after having been stopped by said means, to project them forwardly; and mechanism for removing said means 80 from in front of the articles before said rotatable member engages the latter, substantially as specified.

7. A timing and feeding mechanism of the character described including, in combination: a horizontal guideway having a recess therein through which articles are 85 adapted to fall; means adapted to be moved into the path of articles moving along said guideway to thereby temporarily arrest the 90 same; rapidly movable members having a path of movement over said guideway and adapted to alternately engage articles therein after the same have been arrested by said means, said members serving to project the 95 articles to said recess; and mechanism for timing the operation of said means and said movable members whereby said means are moved to an inoperative position prior to the engagement of the articles by said 100 members, substantially as specified.

8. A timing and feeding mechanism of the character described including, in combination: a gravity feed chute having a horizontal portion at the bottom thereof, 110 said portion being provided with a recess through which articles are adapted to fall by gravity; means intermittently movable to a position to obstruct the passage of articles along said horizontal portion, said 115 means being removed from the recess; and a rapidly rotatable arm having a path of movement above said horizontal portion adapted to engage and project articles to said recess after the articles have been arrested by said means, substantially as specified.
